UNITED STATES PATENT OFFICE.

SHIRLEY VALJEAN WRIGHT, OF TOLEDO, OHIO.

BOX.

No. 905,398.

Specification of Letters Patent.

Patented Dec. 1, 1908.

Application filed December 14, 1907. Serial No. 406,501.

To all whom it may concern:

Be it known that I, SHIRLEY VALJEAN WRIGHT, a citizen of the United States, residing at Toledo, in the county of Lucas and 5 State of Ohio, have invented a new and useful Improvement in Boxes, of which the following is a specification.

This invention relates to a paper box designed to be constructed from a single blank 10 and provided with a discharge spout which folds within the box and when folded forms a cover which will exclude dirt and dust and which when open makes a convenient spout for the discharge of the contents of the box. 15 The box is especially designed for cereals, flour, coffee, spices and articles in a powdered form.

The invention consists of the novel features of construction hereinafter described, 20 pointed out in the claim and shown in the accompanying drawings, in which

Figure 1 is a perspective view of the box, the spout being open. Fig. 2 is a plan view of the blank from which the box is formed. 25 Fig. 3 is a plan view of the complete box closed. Fig. 4 is a horizontal section taken through the box. Fig. 5 is a section on the line 5—5 of Fig. 3. Fig. 6 is a detail view 30 partly in section showing a locking finger carried by the spout.

In forming the box I provide a blank A, the body portion of which forms the sides of the box and this blank is folded lengthwise as indicated by the dotted lines B and is 35 cut transversely as shown at C, said cuts extending from the side edge of the blank to the adjacent line of fold B. This forms overlapping bottom portions D and smaller inner bottom flaps D' which when the box is 40 folded meet each other as shown in Fig. 4 thus forming a smooth bottom, the said bottom flaps being supported by the overlapping bottom portions D. Top portions, E, E', and E² are likewise formed upon the 45 side of the blank opposite the bottom portions, the top flap E² having one corner segmentally cut away. End portions E⁴ are also cut out, the cut-out portions being entirely removed from one of these end portions 50 while adjacent the other a semi-circular flap F is left, which when the box is folded is folded centrally and transversely upon itself to form a spout. The extreme

ends of the body portion are bent to form small end flaps H and the end portion H' 55 adjacent the spout portion F has an opening G' cut in the corner adjacent the line of fold of the spout F and at this end of the blank one of the bottom portions is entirely removed as shown at D². This leaves the end 60 portion H' as an extra fifth side.

When the box is folded the body portion A forms the sides, the bottom being formed by the bottom portions D and D' and the top by the folding over of the top portions 65 E, E' and E². One of the cut-out top flaps E⁴ folds inwardly upon the under side of the top while the other one folds over upon the top portion E², its curved edge resting parallel to but a slight distance from the curved 70 edge of the cut-out portion of said top portion E². When the spout F is folded down as shown in Fig. 3 it rests upon this marginal portion of the top portion E², the top 75 of the spout when closed lying flush with the top of the outer flap E⁴. To hold the spout in a closed position and to form a guide for one side of the spout to work in, a fifth side H' is folded over the end of the box adjacent 80 said spout and a space is thereby formed between said end portion H' and the body portion A in which a side of the spout works and is provided with a finger F' which engages the under side of the box top when the spout is drawn out, thereby 85 limiting outward movement of the spout and preventing it from being entirely withdrawn from the guide way in which it works.

Having thus fully described my invention, 90 what I claim as new and desire to secure by Letters Patent, is:—

A box having a top formed of a plurality of flaps, a portion of which are segmentally cut out, one of said cut out flaps folding 95 over the other and leaving a curved marginal portion upon the under flap exposed, and a folding spout carried by the box, and resting when folded on said marginal portion, the top of the spout being flush 100 with the upper flap.

SHIRLEY VALJEAN WRIGHT.
